METHOD OF FORMING A FUEL CHARGE
FOR INTERNAL COMBUSTION ENGINESArthur R. Baker, Indianapolis, Ind., assignor, by
mesne assignments, to Columbia Carburetor
Company, a corporation of Delaware

Application November 19, 1931, Serial No. 576,172

4 Claims. (Cl. 48—212)

This invention relates to carburetion and a general object of the invention is to provide a new and improved method of carburetion for internal combustion engines.

5 Another object is to provide a method of carburetion by which low grade gasoline or other motor fuel may be efficiently used.

A further object is to provide a new method 10 of carburetion by which excessive detonation may be reduced even when using low grade fuel enabling the operator to secure the same or better results with a low grade gasoline than are secured by other methods with so-called highest or "anti-knock" gasoline.

15 A further object is to provide a method of carburetion in which detonation may be reduced without the use of an excess of fuel.

Other objects and advantages will become apparent as the description proceeds.

20 This application is a continuation in part of my copending application Ser. No. 457,362, filed May 29, 1930 for Carbureters, now Patent No. 1,877,117.

25 Referring to the accompanying drawings, which are made a part hereof and on which similar reference characters indicate similar parts,

Figure 1 is a side elevation of the carburetor as normally mounted in operative position on 30 an engine,

Figure 2, a view in elevation from the opposite side of that shown in Figure 1;

Figure 3, a view in elevation looking from the right, as shown in Figure 1,

35 Figure 4, a section on line 4—4 of Figure 3, looking up,

Figure 5, a section on the same line looking down, as indicated by the arrows in Figure 3,

Figure 6, a vertical section taken substantially on line 6—6 of Figure 2,

Figure 7, a section on line 7—7 of Figure 5,

Figure 8, a detail view of the throttle valve,

Figure 9, a section on line 9—9 of Figure 7,

Figure 10, a section on line 10—10 of Figure 6,

45 Figure 11, a section on line 11—11 of Figure 5, and

Figure 12, a modified form of gasoline metering valve.

In the drawings numeral 20 indicates the casing 50 of the lower section and 21 the casing of the upper section of the carburetor. These are secured together by a bolt, a gasket 19 being secured between them to provide the necessary seal. The lower casing is provided with an enlarged air intake port 22, said intake port be-

ing provided with the usual choke butterfly valve 23 which valve is operated by a crank arm 24 having a pin 25 to which may be attached an operating lever. In place of the arm shown, any other suitable mechanism for operating 5 the butterfly valve may be provided. The upper casing 21 has a flanged portion 26 by means of which the carburetor is attached to the intake manifold 27 on the engine. The casing 21 is provided with a port 28 to which is attached a 10 pipe, not shown, leading from a supply of fuel. The fuel entering through the port 28, drops into a pan 29 and when this is filled it overflows into a well 30 in which is a float 31, said float being pivoted at 32 by means of an arm 33, said arm resting beneath a valve 34 which controls the gasoline port. The arm 33 is sufficiently resilient to take care of any pulsations of the engine without disturbing the valve 34. From the construction just described it should be evident that the float 31 will maintain a predetermined level of fuel in the well 30 since when the float rises, the arm 33 pressing upwardly on the valve 34 will close the inlet port. Pan 29 has a 15 hole drilled through the floor at 35 through 20 which a tube 36 extends, the lower end of the tube being well down within the fuel well to draw fuel from near the bottom. A shoulder 37 is positioned around the bore to prevent fuel from flowing from the pan 29 directly down 25 through the hole 35. A tube 38 is likewise positioned within a bore 39 in the pan 29. This tube is slotted as shown at 40. While the greater portion of the slot in the tube will be normally below the level of the fuel in the well, a portion of it will be above the level of the fuel, the function of which will be presently more fully explained. Surrounding the slotted tube is a 30 sleeve 41 which is secured in the bore 39. This sleeve has a venturi 42 near its upper end. Within the lower end of the sleeve 41 is pressed a plate 43 which has walls 44 forming a cup into 35 which the lower end of the tube 38 dips.

The sleeve 41 is provided with a number of ports 45. The tube 38 is secured in the upper 40 casing 21 and connects with an air intake port 46 in the top of the casing. The purpose of the tube 38 is to provide an intake for air, which air will be drawn through the fuel in the cup. The air therefore is washed by the fuel and takes 45 up a portion of the more easily volatilized elements of fuel so as to provide in substance a very lean fuel air mixture of a partly carbureted air.

One purpose of having the slot 40 in the tube 50

55

38 extend above the fuel level is to allow the cup to be filled by fuel prior to operation of the engine. A second object of having the slot in this position is that during low or idling 5 speed there may not be sufficient suction to draw the air through the fuel in which case it will be drawn from above the fuel through this slot 40. The casing 21 is dome-shaped and the space 111 above the fuel provides a relatively 10 large expansion chamber into which partly carbureted air expands, and in which its velocity is reduced to allow any liquid fuel to drop back 15 into the body of the fuel in the pan.

The tube 38 not only functions to load the air 15 with fuel vapor but serves also another purpose. Air is drawn down through this tube and passes up through the fuel. As it passes up through the venturi at 42 it acts as a pump to force fuel up around the tube 38 and to deposit 20 it in the pan 29.

The tube 36 is secured in the cover 21. This tube 36 enters through the port into a chamber forming the enlarged end of a bore 48 which extends through the casing 21. A sleeve 49 is 25 threaded into the bore at 50. A tube 51 is also threaded at 52 into the bore and this tube is surrounded by and radially spaced from the tube 49. The tube 51 has a restricted opening 53 at its outer end and a valve rod 54 is positioned 30 within the tube 51 and has a valve 55 positioned adjacent the restricted opening 53. The end 55 which forms the valve is made of such a size as neatly to enter the restricted opening 53 and close off the opening without actually engaging 35 a valve seat. The valve rod 54 is secured to a bellows 56 which bellows in turn is secured to a nut 57 which is screw-threaded into the outer end of the bore 48. The end of the rod 54 is likewise screw threaded at 58 to receive 40 a screw cap 59 which cap is threaded within a bore in the nut 57 at 60. The purpose of the screw 59 is to move the rod 54 axially to adjust the size of the opening 53 around the end 55. As shown in Figure 10 the rod 54 is grooved 45 axially to provide a passage for fuel between the rod and the tube 51. The threads 60 on the screw plug 59 must necessarily be of a different pitch from the threads 58 on the end of the rod 54 so that when the screw 59 is turned in either direction there will be an axial movement 50 of the rod 54. For example, assume that the threads on the plug 59 are 20 pitch threads, and the threads on the rod 54 are 40 pitch threads, then one revolution of the screw 59 will move 55 the rod 54 1/40th of an inch. If, however, the threads 58 should be made right-hand threads and the threads 60 left-hand threads then one revolution of the screw 59 would move the rod 54 axially 3/40ths of an inch. A nipple 61 is 60 screw threaded into the end of the bore 48 opposite the plug 57 and a cap or cup 62 is secured upon the end of this nipple. The cap or cup 62 will be positioned in the path of the exhaust manifold 108 from the engine so as to heat the fuel which passes from the tube 51. The heated mixture then passes around the outside of the 65 tube 48 and into a chamber 63 from which it passes into an axial bore 64 from which it passes through radial bores 65 over the edge of a cup 66. The fuel passing over the edge of the cup 66 mixes with air coming in through the intake 22 from which it passes through the expansion chamber 67 through which it enters 70 into the intake manifold 21 of the engine.

Extending up through the head 112 surround-

ing the axial passage 64 is an axial bore into the lower end of which is inserted a short tube 113, the lower end of which extends down within the dished portion of the cup 66. Under certain circumstances, as at slow or idle speeds, 5 some portion of the fuel issuing from the nozzle 53 may fall into the cup 66 as a liquid. In case this happens such liquid fuel will be drawn up through and delivered into the stream of fuel being drawn into the engine. This feature 10 smooths out to a certain extent the running of the engine at slow or at idling speeds.

A pipe 68 is secured to the air intake 22 in order to draw air from a point distant from the engine so as to insure that relatively unheated 15 or normal air is drawn into the carburetor instead of the heated air adjacent the hot portions of the engine.

The suction through the passage 67 will create an aspirating effect around the cup 66 which in 20 turn through the annular passage 69 will create a vacuum above the liquid surrounding the tube 38. This will create a suction down through the tube 38 and draw air through this tube which air will pass partly through the slot in the tube 25 and partly through the end of the tube up through the fuel in the well. Air laden with a small percentage of fuel will therefore be drawn through a port 114 into the annular passage 69. This air will in turn create a suction through the 30 restricted port 53 and draw fuel through the tube 36. As the fuel issues through the restricted nozzle 53 it will become heated by contact with and by heat radiated from the casing 62 which projects into the exhaust gases from the engine. 35

In Figure 12 is shown a modified form of valve. The end 115 of this valve is in the form of a disk.

In some carburetors now in use the fuel is raised from the fluid level to the jet a distance of $\frac{1}{8}$ th to $\frac{1}{4}$ th of an inch. This is due to the fact that there is only a very low suction created at the end of the spray nozzle. In the carburetor forming the subject matter of this invention the liquid is raised approximately $1\frac{1}{2}$ inches. This is possible because of the fact that a relatively 45 high suction is created at the spray nozzle in this carburetor. Of course the fact that the fuel is raised a greater height than in other carburetors in and of itself is relatively unimportant but the fuel is raised this height because of the 50 relatively high suction which is created at the spray nozzle 53. This high suction serves to more completely atomize fuel than is possible in other carburetors. The high suction claimed is brought about by a combination of the following operations: 55

The cold air which is drawn through the pipe 68 travels through the Venturi throttle valve and past the cup 66. When the throttle is wide open there is a large volume of air passing through 60 the carburetor, although at a relatively low velocity. The restriction between the venturi and the cup 66 increases the velocity, however, sufficiently high to create a relatively high suction through the ports 65, this suction pressure being 65 transmitted to the end of the annular passage 69 around the nozzle 53. The volume of air issuing through the axial passage 64 caused by this suction serves in turn to reduce the pressure at the nozzle 53 to create an additional high suction 70 through the tube 51. This suction, of course, serving to draw the fuel from the well up through the tube 38. It will be apparent therefore that the suction created at 65 plus the suction created 75 at 53 causes a relatively high suction to the fuel.

which is drawn through the tube 36 which of course makes it possible to elevate the fuel to a much higher level than was possible with the older carbureters. One result of the high suction 5 at the nozzle 53 is to atomize the fuel as it issues from this nozzle into the hot cap 62, and to more thoroughly mix the fuel and air at this point.

Shown in detail in Figure 8 is the Venturi-shaped throttle valve, this consists of a sleeve 70 10 slidably positioned within the bore 71 and is guided by an arm 72 which slides on the lower end of a rod 73 which depends from the cup 66. The upper end of the cup 66 is screw threaded at 74 within the passage 63. The purpose of this 15 threaded engagement is to provide means for adjusting the cup 66 for a purpose which will later appear.

The sleeve 70 may be provided with a packing ring 75. The upper inner end of the sleeve 70 is 20 tapered as shown at 76. Vertical adjustment of the sleeve 70 will control the opening between the tapered side 76 of the sleeve and the edge of the head 112 to control the amount of fuel which may pass to the engine. The sleeve 70 is shaped 25 with a shoulder portion 116 which cooperates with a tapered lower side 117 of the cup 66. In operation when the sleeve is in its partially closed position the air stream is deflected radially by the taper 117 to create a suction between the 30 head 112 and the cup 66. When the sleeve 70 is wide open the incoming air has a more direct path through the venturi. There is now, however, a larger volume of air passing through the 35 valve. This is deflected radially by the taper 116 into the enlargement around the head to create a strong suction through the annular nozzle between the cup 66 and head 112. The cup 66 preferably will be adjusted so as to provide entrance of the necessary fuel to the engine 40 during idling speed when the throttle is normally closed.

The rod 73 may be manually rotated by means of a wing nut 96, or other means clamped to it so as to adjust the cup 66 with respect to the 45 head 112.

When the sleeve 70 is pushed down sufficiently far its lower end engages a disk 77 to which is attached a valve 78. The valve is normally closed by a spring 79, as shown in detail in Figure 7. 50 The valve 78 controls passage of fuel from the pan 29. An air port 80 is drilled through the side of the casing and connects with an annular passage 81 around the valve. The valve is provided with a tube 82 through which the fuel 55 entering through the valve 78 and the air which mixes with it from the port 80 enters within the venturi. When the throttle is open wide therefore the venturi gives an increased supply of fuel with a mixture of air as just described. The 60 suction past the tube 82 will create suction to draw the fuel and air into the fuel charge. The arm or bracket 72 has a pair of curved portions 83 which fit in an annular groove about the venturi. The arm 72 is provided with a screw-threaded hole 84 to receive the end of an operating pin 85.

Positioned beneath the valve 78 is a piston 86 which is provided with an axial bore 87 which is 65 normally closed by a ball or other suitable valve 88. The spring 79 is seated upon a plate 89 pressed within the upper end of a chamber 90 formed in the upper end of the piston 86. The piston 86 in turn is slidable in a casing 81, the lower end of which is provided with a port 92 70 which is also closed by ball or other valve 93.

The valve 93 controls entry of fuel through a bore 94 which bore is connected to the fuel pan 29. When the piston 86 is forced down fuel is forced up through the port 87 and out through radial port 118 into the intake channel 71. The 5 bore 94 which extends up through the casing connects with a tube 95 which is bent over and the lower end terminates slightly above the bottom of the fuel in the pan 29. The purpose of the bowed end 95 is to prevent fuel from freely 10 flowing by gravity from the pan 29 through the valve 93 into the chamber beneath the piston 86. Should the fuel be allowed to flow freely by gravity a spring-pressed ball at 92 might be necessary 15 or at least a valve which was closed by some positive pressure means or else a much heavier ball valve than 93 would be required.

As shown at 110 in Figure 11 there is a sloping wall to the pan 29. The purpose of this is so 20 that fuel will be held in the pan when the car is on a steep incline. Without this inclined wall the fuel would flow to the low side of the carburetor so that none would be drawn into the engine when on a steep hill. In going down hill 25 the operator frequently desires to accelerate the speed of the car near the foot preparatory to climbing another hill in front. Unless there were a wall such as 110 the fuel would all fall to the front of the carburetor.

The venturi which constitutes the throttle 30 valve is operated by means of a toggle arrangement shown in Figure 2. This consists of an arm 97 pivoted on a screw 98 which is secured in the side of the casing 20. The arm 97 carried a pin 99 near its upper end to form a stop member. An arm 100 is rigidly secured to the side 35 of the arm 97 and provided with a ball 101 at its outer end to form means for attaching a lever thereto for operating the throttle.

A link 102 is pivoted to the arm 97 at 103 and 40 is pivoted at its other end to the pin 85. To open the throttle the lever arm 100 is moved in the direction of the arrow shown in Fig. 2. As will be seen the first movement of this lever will move the throttle valve very slightly which in 45 substance provides a lever having a rather high mechanical advantage at the opening of the throttle with only a slight movement of the throttle. As the arm 100 proceeds in the direction indicated a given movement of the arm produces a relatively greater opening of the throttle until the throttle is moved to a fully open position. As the toggle moves further to open position it ceases to operate as a toggle and becomes 50 a positive lever. The pin 85 is held in an eccentric bearing 104 which bearing is clamped between the ends 105 of the link 102. Rotation of the bearing 104 serves to adjust the opening of 55 the throttle for idling position.

Adjustably mounted on the side of the intake manifold 27 is a rod 106. This rod carries on its lower end a wedge-shaped member 107 which fits between the side of the upper casing 21 and the exhaust manifold 108 of the engine. The purpose of the wedge 107 is to provide means 60 for controlling the amount of heat passing from the exhaust manifold to the body of the carburetor. A nut 109 may be provided for vertically adjusting the wedge. It should be apparent that 65 when the wedge is tightly fitted between the exhaust manifold and the body of the carburetor that it provides a good heat conducting medium but when it is raised out of contact with these elements there is an air space between them 70 which serves as a heat insulating medium. 75

Under certain circumstances I may provide means for automatically adjusting the wedge as for example in response to temperature changes.

5 *Operation*

The operation of the carbureter is as follows: Fuel is taken in through the line 28 and drops into the pan 29 filling this pan up to the top of a wall over which the remaining fuel then 10 spills into the well 30. The throttle valve 70 is depressed by means of the toggle mechanism shown in Figure 2. Upon the suction stroke of the engine air is drawn into the engine. This creates a suction around the cup 66 which suction 15 together with the velocity of the air streaming past the cup creates a vacuum to draw air through the annular passage 69. The air enters this passage from the following course. First it comes into the casing through the air intake 20 port 46 and passes down through the tube 38. Some of the air passes out through the slot 40 and up through the fuel in the well. Another and large volume of the air passes down through 25 and out past the end of the tube 38 and up through the fuel during which course it takes up certain portions of the volatilized fuel. This air with its charge of fuel enters through port 114 into the annular passage 69 just mentioned. The 30 velocity of the air traveling up around the tube 38, which velocity is increased by the venturi 42, acts as a pump to raise fuel from the well and deliver it into the pan 29. The velocity of the air together with the suction as the air passes out of the tube 51 creates suction within the tube 48 35 around the valve stem 54 to suck fuel through this tube. The fuel and the air become heated in the cap 62 which projects into the exhaust manifold of the engine. This is a mixture of fuel which is too rich to fire. This mixture, however, 40 passes down through the chamber 63 and out through the ports 65 into the cup 66 where it is sucked and aspirated into the air which is being drawn in through the tube 68.

Analysis of the fuel charge in the cap 62 reveals 45 that there is an appreciable amount of non-condensable gas or gases present in the cap. Among these gases are carbon monoxide and hydrogen. The formation of these gases is thought to be the result of a partial distillation which takes place 50 in a partial vacuum under the heat from the exhaust manifold. In other words there is a vacuum distillation of the hydrocarbon fuels with a mixture of oxygen. The hydrocarbon fuels are partially broken down into hydrogen and a part 55 of the carbon unites with oxygen to form carbon monoxide without, however, any actual combustion taking place. Of course, while it is believed no combustion, properly speaking, takes place nevertheless there may be a partial combustion. 60 In any case there is formed an appreciable amount of non-condensable gas in the form of hydrogen and carbon monoxide formed in the cap 62. These gases are thoroughly dispersed through the fuel charge and are carried over into 65 the engine and form a means for conducting the ignition flames through the fuel charge in the engine. These gases therefore serve to ignite the remaining fuel charge through its whole body substantially at the same time. The fuel body, 70 however, is not an explosive gas but is a relatively slow burning fuel mixture. This results in an anti-knock or substantially non-detonating fuel charge.

Whenever the throttle is open it is desirable 75 to increase momentarily the charge of fuel de-

livered to the engine. This is provided by means of a plunger 86 which acts as a pump to inject a small volume of fuel at each time the opening of the throttle is increased. The mechanism for doing this is shown in detail in Figure 7, and consists of the plunger 86 operated in a cylinder 91. As the throttle is opened a bracket 120 on the arm 12, which normally supports the plunger 86 by means of a lug 121, allows the piston 86 to be forced down by the spring 79. As the piston is 10 forced down fluid is forced out through the port 87 past the check valve 88 and out through the ports 118 into the main air stream where it is sucked into the engine. When the plunger 86 is raised again fuel is drawn into the cylinder 91 15 again so that this cylinder is kept filled with fuel. It is desirable at relatively high speeds to increase the supply of fuel delivered to the engine. Mechanism for doing this is shown in detail in Fig. 7. When the throttle 70 is opened very wide the velocity of the air drawn past the cup 66 is decreased, this would tend to decrease the aspirating effect upon the gas and air being drawn in from the chamber 64. The lower end of the venturi 70, however, when this venturi reaches 20 a certain predetermined level, strokes the disk 77 and opens the valve 78. This allows fuel to flow by gravity from the pan 29 through tube 82 within the venturi. The fuel as it flows through this valve is mixed with air which is drawn in through the radial port 80, the air entering through this port sufficiently volatilizes the fuel to make it easily drawn into the venturi where it is mixed with other air being drawn in through the port 22. Should the valve 78 be held open for 25 any reason after the car comes to a stop it should be evident that a certain amount of fuel will leak out, only that in the pan 29, however, will leak out.

As stated in the objects of the invention one of 40 the purposes sought to be accomplished by this carbureter is to secure the same or better results with low test gasoline or other fuels as are being secured by the so-called anti-knock or "doctored" fuels. This is done by delivering to the engine a 45 fuel which is thought to have a rather dense or fog-like supply of vapor which is not readily explosive but rather which will be burned in the engine as it becomes ignited by the gases which are explosive. This supply of dense vapor is 50 thought to be delivered to the engine for the following reasons:

The high velocity of the air which is drawn through the passage 69 carries with it a relatively large volume of fuel drawn in through the nozzle 55 53. This fuel and the air are heated to a relatively high temperature in the tube 62. The amount of fuel taken up by the air is somewhat in excess of the amount that will be readily vaporized when the whole comes in contact with 60 the cold air drawn in through the pipe 68, i. e. when the whole supply has been reduced to a low temperature by the cold air from 68 some of the fuel will be in suspension in the air somewhat as a fog. This fuel will be drawn into the engine 65 and will supply a slow burning fuel charge in the engine. The burning of this fuel charge will develop power during the stroke of the piston rather than forming a part of an instantaneous explosion, i. e. the pressure within the cylinder will 70 gradually increase as the fuel charge burns in a manner somewhat analogous to the burning of a charge in a cannon in which the powder charge continues to develop pressure until the shot has reached the mouth of the cannon. It will there- 75

fore be seen that if the above theory is correct the pressure in the cylinder is maintained for a longer period during the stroke of the piston than is true with fuels which explode instantly. It should be obvious furthermore that the detonation will be considerably decreased.

One fact which assists the air which is drawn through 69 in becoming so well saturated with fuel gasoline is the fact that this air is drawn or bubbled through the fuel in the well and takes up a certain amount of the more highly volatile fuels so that the air enters the tube 62 with a certain amount of fuel which has been "taken aboard" so to speak, at a relatively low temperature. This then, when heated in the tube 62, will become more heavily laden with fuel than would otherwise be the case, or in other words, it would require a higher temperature in the tube 62 to enable a given quantity of air to take up the desired amount of fuel.

It should be noted from the description and from the operation just given that the fuel is aerated through all of its movements in the carburetor as well as being churned up and thus aerated in the fuel pan and well. For example in the well it is aerated by the pumping action of the air which passes out through 38 up through the fuel. Thus the fuel is most completely aerated and then into a stream which ultimately issues into the stream of fuel going into the engine. This is an important fact for it means a more perfect fuel charge entering the engine for the purpose in mind.

It will be obvious to those skilled in the art that various changes may be made in my device without departing from the spirit of the invention and therefore I do not limit myself to what is shown in the drawings and described in the specification, but only as indicated by the appended claims.

Having thus fully described my said invention, what I claim as new and desire to secure by Letters Patent, is:

1. The method of forming a fuel charge for internal combustion engines which consists in drawing air through a body of fuel by the engine suction to saturate said air with fuel sufficiently to form a carbureted mixture which is too rich to fire, heating this mixture at the point of mixture to a temperature above the ignition point of a normal charge of the fuel to form an appreciable amount of free hydrogen and free carbon monoxide gas and thereafter mixing relatively cold air with the resulting mixture whereby a slow burning fuel charge is formed having a mix-

ture of highly inflammable free gas therein, substantially as set forth.

2. The method of producing a fuel charge for an internal combustion engine which consists in mixing together a relatively small quantity of partially carbureted air with a relatively large quantity of fuel to form a fuel in a mixing chamber the walls of which are maintained at a higher temperature charge which is too rich for complete combustion, simultaneously heating the same by the walls of the chamber to a temperature above the ignition point of a normal charge of the fuel to form an appreciable amount of free hydrogen and carbon monoxide gas, and reversing the flow of the fuel charge during the heating, the heavier fuel elements being projected against the sides of the mixing chamber whereby liquid fuel is vaporized and heated and the lighter vaporized fuels are mixed with incoming cold air, mixing this combination of air and fuel with a large volume of relatively cold air to form a fuel charge, the cold air functioning to condense certain portions of the fuel and keep it in suspension in a fog-like form, substantially as set forth.

3. The method of preparing a fuel charge for internal combustion engines which comprises aspirating a liquid fuel into the suction path of a stream of air, said aspirating action creating a fuel mixture too rich to fire, heating said fuel mixture at the point of mixture to a temperature above the ignition point of the fuel in a normally explosive condition, creating an appreciable amount of non-condensable combustible gases during said heating and thereafter adding a relatively large volume of cool air to form the fuel charge, the addition of the cool air serving to condense an appreciable amount of the fuel charge to effect a fog-like condition in the fuel to create thereby a relatively slow burning fuel charge, substantially as set forth.

4. The method of forming a fuel charge for internal combustion engines which comprises delivering liquid fuel and air into a mixing chamber under such velocities as will cause the heavier liquid element to separate from the lighter gaseous elements mixing together the liquid fuel and the air and heating the mixture at the point of mixture, said heating being conducted so that the liquid portions of the fuel will be heated more rapidly than the lighter portions in order to gasify the entire mixture more quickly, adding to the mixture a large volume of cool air to form a volatile fuel charge.

ARTHUR R. BAKER. 55
